CALENDAR-TYPE LIPSTICK HOLDER

Julius A. Welebny, Rockville Centre, N. Y.

Application March 6, 1953, Serial No. 23,925

Term of patent 7 years

(Cl. D86—10)

To all whom it may concern:

Be it known that I, Julius A. Welebny, a citizen of United States of America, residing at Rockville Centre, in the county of Nassau and State of New York, have invented a new, original, and ornamental Design for a Calendar-Type Lipstick Holder, of which the following is a specification, reference being had to the accompanying drawing, forming part thereof.

In the drawing:

Fig. 1 is a front view of a calendar-type lipstick holder, showing my new design;

Figs. 2 and 3 are left and right end views respectively of Fig. 1; and

Fig. 4 is a partially exploded top plan view.

I claim:

The ornamental design for a calendar-type lipstick holder, substantially as shown.

JULIUS A. WELEBNY.
